UNITED STATES PATENT OFFICE.

JOHN ALEC MORRISON, OF KELOWNA, BRITISH COLUMBIA, CANADA.

DISPLAY-RACK.

1,061,625.

Specification of Letters Patent.

Patented May 13, 1913.

Application filed July 11, 1912. Serial No. 708,786.

To all whom it may concern:

Be it known that I, JOHN A. MORRISON, a subject of the King of Great Britain, residing at Kelowna, British Columbia, Canada, have invented certain new and useful Improvements in Display-Racks; and I do hereby declare that the following is a full, clear, and exact description of the invention, such as will enable others skilled in the art to which it appertains to make and use the same.

The invention to be hereinafter described relates to display racks.

In order to more clearly disclose the construction, operation, and use of the invention, reference should be had to the accompanying drawings forming part of the present application.

Throughout the several figures of the drawings like reference characters designate the same parts.

In the drawings: Figure 1 is a perspective view of the invention, complete; Fig. 2 is a similar view, showing a plurality of spacing wires; Fig. 3 is an enlarged, longitudinal, cross section, showing the connections; and Fig. 4 is a perspective view, showing a plurality of the racks in position in a case.

The main objects of the invention are to provide a simple, efficient, durable, compact, and economical display rack in which the goods may be readily seen at all times without opening the rack or withdrawing it from its place. The advantages of such are obvious and need not here be pointed out.

Referring to the drawings in detail, 1 indicates a base or bottom board. A plate of glass or other transparent material 2 is secured to the front end of this base by means of a metal clip or binder 3 which extends across the front and a short distance along each side, as shown in Figs. 1 and 2. This binder consists of a narrow rigid strip or band of metal fitting tightly against the front of said glass plate at the bottom thereof, and provided with short terminal wings or extensions at right angles to the main part of said strip, these wings passing across the side edges of the said glass plate and slightly overlapping the contiguous parts of the base 1. This clip is secured in place by means of screws 4 passed through it, through the glass pane 2, and into the base 1. Similar connecting screws are passed through the ends of the clip and into the sides of the base. It is essential, of course,

to brace the glass strongly in its upright position. Otherwise, it will be snapped off short at its lower edge, along the line of the clip. To this end, a pair of wire rods 5 are provided, one for each side. Each of these rods has one end reduced to form a shoulder 6 and threaded, as at 7, to receive a binding nut 8. The threaded part 7 is passed through a small bore in the pane and the nuts 8 are then screwed tightly home, clamping the rods to the frame. As soon as the rods are thus secured, their opposite ends are made fast to the base by means of screws passed therethrough and turned into the base—all as clearly shown in Fig. 3. Preferably, each brace 5, from the point of connection with the base, is bent into loop form of U, V, or other suitable shape. This loop (the U form, only, is shown) constitutes a side member for retaining the articles on the base. The end of the loop is provided with a notch in its side to receive a fastening pin 9 to secure it in place. Thus, it will be evident that the entire rack may be readily and quickly knocked down or set up, at will. Between the side members may be arranged any number of spacing wires for separating or grouping the articles. Such an arrangement is clearly shown in Fig. 2. These wires may each be held in place in the same way as above disclosed.

It is obvious that other materials may be substituted, for glass, but glass or other transparent material is preferred because it permits the articles to be easily and quickly seen at all times. When the front is made of glass and a considerable number of the racks are arranged in rows and tiers, the assembling gives the appearance of a large glass front case with all articles clearly visible and, at the same time, amply inclosed and protected.

It is thought that the operation and use of the invention will be clear from the preceding detailed description.

Changes may be made in the construction, arrangement, and disposition of the several parts of the invention without in any way departing from the field and scope of the same, and it is meant to include all such within this application wherein only a preferred form has been disclosed.

Having thus fully described my invention, what I claim as new and desire to secure by Letters Patent is:

In combination with the base of a display

rack, a transparent front plate, a metal strip fastened to said base and against the front of said plate and oblique bracing rods fastened to said plate and base and prolonged 5 to form in the rear of their points of attachment to the latter raised wire supports for articles to be exhibited.

In witness whereof I have hereunto set my hand in the presence of two witnesses.

JOHN ALEC MORRISON.

Witnesses:

THOMAS N. MORRISON,

ROBERT JAMES COPELAND.
